VALVE MECHANISM.

1,141,376.

Specification of Letters Patent.

Patented June 1, 1915.

Application filed April 6, 1914. Serial No. 829,862.

To all whom it may concern:

Be it known that I, JAMES G. BUCHANAN, a citizen of the United States, and a resident of Cananea, Sonora, Mexico, have 5 made certain new and useful Improvements in Valve Mechanisms, of which the following is a specification.

My invention relates to improvements in valve mechanisms to be used on railroad 10 cars, and it consists in the combinations, constructions, and arrangements herein described and claimed.

An object of my invention is to provide 15 a device which is to be used in connection with an automatic triple valve for setting brakes either by applying excess air pressure which is carried on the engine, to the train line air pressure, or by the use of automatic air pressure as is now used, or by both 20 excess air pressure and automatic air pressure combined.

Other objects and advantages will appear 25 in the following specification and the novel features of the device will be particularly pointed out in the appended claims.

My invention is illustrated in the accompanying drawings forming part of this application in which—

Figure 1 is a section through my im- 30 proved valve mechanism, Fig. 2 is a section at right angles to Fig. 1 on the line 2—2 of Fig. 1, and Fig. 3 is a diagrammatic view showing the application of the improved valve mechanism to a train controlling 35 means.

In the following specification I will de- 40 scribe completely the novel valve mechanism and the operation thereof and only so much of the ordinary mechanism which co- operates therewith as will be sufficient for a 45 clear understanding of the use and operation of my invention.

In carrying out my invention I provide a 50 valve casing 1 of suitable shape. In the present instance I have shown this as a cylinder having a top 2 which may be secured to the body portion by means of bolts 3 or in any other suitable manner.

Within the interior of the valve casing is 55 a valve member 4. This consists of a weight which is provided at its upper end with a conical-shaped closure member 4^y and at the bottom with a similar member 4^x. The closure member 4^y is arranged to enter the opening 5 which is provided with a valve

seat 6. The lower valve member 4^x is arranged to control a port 7, a seat 8 being provided against which the valve may be engaged.

In the body portion 1 below the chamber 60 in which the valve 4 operates is a cylindrical bore 9 in which is disposed a cylindrical piston valve 10. A screw plug 11 is provided for closing the end of the bore and has a projecting portion 11^x for limiting the 65 movement of the piston valve toward the plug. At 12 is shown an exhaust port. A port 13 communicates with the interior portion 9 of the bore at one end and with a pipe 14 at the other end. The pipe 14 communicates in turn with a triple valve, as 70 shown in Fig. 3.

The lower end of the valve casing 1 has a threaded opening 15 arranged to receive a pipe 16 leading from the main train pipe. 75 A passage 17 connects the threaded opening 15 with the port 7.

From the foregoing description of the various parts of the device the operation 80 thereof may be readily understood.

Let us assume that excess air pressure is supplied to the main train line at the engine. In Fig. 3 I have shown the pipe 16 as being connected directly to the drain plug of the automatic triple valve. Air passes from 85 the main train line through pipe 16, thence through the passage 17 and port 7 where it unseats the weighted valve 4. This allows the air to pass the valve member 4^x and thence by means of the passage 18 into the 90 bore 9, thus forcing the piston valve 10 in the direction shown by the arrow in Fig. 1. This uncovers the passage 13 and covers the exhaust port 12. The air now flows through the passage 13 and through the pipe 14, and 95 is delivered through this pipe to the exhaust of the triple valve and on to the brake cylinder, thereby setting or applying the brakes. It will be understood that one of these improved "straight" valve mechanisms will be used in connection with the 100 automatic triple valve on each individual car.

When the brake has been set as above described, the excess air pressure which was 105 applied at the engine and used to set the brake has been reduced to slightly less than the automatic or auxiliary pressure by the excess pressure going into the brake cylinder. This causes the automatic triple valve 110

to move to lap or to cover the exhaust port, thereby retaining the air pressure in the brake cylinder and also prevents this air pressure from returning to the "straight" 5 air valve and releasing the brake.

In order to release the brake the train air line pressure is increased at the engine sufficiently to push the automatic triple piston and valve to release position, thus opening 10 the exhaust cavity and allowing the air to return from the cylinder through the pipe 14 against the end of the piston valve 10, thus forcing this piston valve to its original 14 position and opening the exhaust port 12, 15 allowing the air to escape to the atmosphere.

The amount of excess pressure added to the train line pressure, as above described, and which is necessary to set the brake with my improved "straight" air valve also increases 20 the pressure in the automatic air auxiliary reservoir. This excess amount of air discharges as automatic air to the brake cylinder at the time the automatic triple valve is moving to lap as above described, thereby again reducing the air pressure in 25 automatic air auxiliary reservoir to the train line air pressure, the handle of the engineer's brake valve on the engine through which the excess air pressure is applied to the train 30 line air pressure, being now in running position.

It will thus be seen that it depends entirely on the amount of excess air pressure which the engineer adds to the train line air 35 pressure how hard the brakes are set on each car, as he has complete control over this by the use of the engineer's brake valve on the engine.

As before mentioned, by the use of my attachment or straight air valve the brakes can be applied by both the use of straight air and automatic air. Straight air can be applied to the brakes and automatic air applied on top or automatic air can be applied 40 to the brakes and straight air can be applied on top, but by the use of my valve it is best to use straight air in all cases, thereby having the automatic air in reserve in case of accident, such as the parting of a hose or 45 breaking of a train pipe. As is clearly seen, the auxiliary reservoir is kept charged by the use of my valve. Thus it acts as a safety device in case of accident.

With the present system of automatic air brakes it often happens on long grades that the automatic air pressure contained in the auxiliary reservoir is not sufficient to hold the train, whereas by the use of my valve 55 the engineer can apply the brakes by the use of the excess pressure sufficient to hold the train and at the same time have the automatic air in reserve to set the brakes in case of accident as mentioned above. Also by 60 the use of my valve using the straight air, the excess overcharge air pressure applied 65

at the engine is distributed equally through my valve to the brake cylinders, one of which is located on each individual car. This prevents, to a large extent, the parting or breaking in two of the train, as is now 70 very often the case with the present system of automatic air.

Since the weighted valve 4 in my valve mechanism seats itself when the excess or overcharge pressure in the train line has 75 been reduced to normal through the action of engineer's valve, then the pressure retained in the brake cylinder takes effect and forces the piston valve 10 up to the projecting portion of plug 11^x thus opening the ex- 80 haust port 12 and releasing the brakes.

As has been explained above in order to set the brakes with my attachment the engineer applies excess air pressure to the train line pressure. In order to set the brakes 85 with automatic air as now used he reduces the train line pressure. It will be seen that he can set the brakes either with straight or automatic air by the use of the same handle of the brake valve now used on the en- 90 gine as he may see fit.

I claim:

1. In a valve mechanism for air brakes, a casing provided with a main valve chamber, a weighted valve disposed in said chamber, a pipe for connecting one end of said valve casing with a supply of compressed air, a passage within said valve casing normally closed by said weighted valve and adapted to be uncovered by excess of air 95 pressure in the passage, an outlet pipe, and means for establishing communication between said main valve chamber and said outlet pipe, said means being controlled by the pressure of air in said main valve chamber. 100

2. In a valve mechanism for air brakes, a casing provided with a main valve chamber, a weighted valve disposed in said chamber, a pipe for connecting one end of said valve casing with a supply of compressed air, a passage within said valve casing normally closed by said weighted valve and adapted to be uncovered by excess of air 105 pressure in the passage, an outlet pipe, and means for establishing communication between said main valve chamber and said outlet pipe, said means comprising a piston valve disposed within a bore in said valve casing, a passage connecting said main valve casing with said bore, and a passage arranged to be uncovered by the movement of said piston valve for connecting said bore with said outlet pipe. 115

3. In a valve mechanism for air brakes, a casing provided with a main valve chamber, a weighted valve disposed in said chamber, a pipe for connecting one end of said valve casing with a supply of compressed air, a passage within said valve casing normally closed by said weighted valve and 120

130

adapted to be uncovered by excess of air pressure in the passage, an outlet pipe, means for establishing communication between said main valve chamber and said outlet pipe, 5 said means comprising a piston valve disposed within a bore in said valve casing, a passage connecting said main valve casing with said bore, a passage arranged to be uncovered by the movement of said piston valve for connecting said bore with said outlet pipe, and an exhaust passage normally uncovered and adapted to be covered when the piston valve uncovers the passage 10 between the interior of the bore and the outlet pipe.

4. In a valve mechanism for air brakes, a casing provided with a main valve chamber, a weighted valve disposed in said chamber, a pipe for connecting one end of said 20 valve casing with a supply of compressed air, a passage within said valve casing normally closed by said weighted valve and adapted to be uncovered by excess of air pressure in the passage, an outlet pipe, 25 means for establishing communication between said main valve chamber and said outlet pipe, said means comprising a piston valve disposed within a bore in said valve casing, a passage connecting said main 30 valve casing with said bore, a passage arranged to be uncovered by the movement of said piston valve for connecting said bore with said outlet pipe, and an exhaust passage normally uncovered and adapted to

be covered when the piston valve uncovers 35 the passage between the interior of the bore and the outlet pipe, said exhaust passage being covered by the reverse movement of said piston valve.

5. In a valve mechanism for air brakes, a 40 casing provided with a main valve chamber, a weighted valve disposed in said chamber, a pipe for connecting one end of said valve casing with a supply of compressed air, a passage within said valve casing normally 45 closed by said weighted valve and adapted to be uncovered by excess of air pressure in the passage, an outlet pipe, means for establishing communication between said main valve chamber and said outlet pipe, said 50 means comprising a piston valve disposed within a bore in said valve casing, a passage connecting said main valve casing with said bore, a passage arranged to be uncovered by the movement of said piston valve 55 for connecting said bore with said outlet pipe, an exhaust passage normally uncovered and adapted to be covered when the piston valve uncovers the passage between the interior of the bore and the outlet pipe, 60 said exhaust passage being covered by the reverse movement of said piston valve, and a screw plug at one end of said bore for limiting the movement of said piston valve.
